DESIGN FOR A VEHICLE BODY

Giuseppe Russo, New York, N. Y.

Application June 22, 1940, Serial No. 93,188

Term of patent 7 years

To all whom it may concern:

Be it known that I, Giuseppe Russo, a subject of the King of Italy (having declared his intentions of becoming a citizen of the United States) and a resident of the city of New York (Borough of Manhattan), in the county and State of New York, have invented a new, original, and ornamental Design for a Vehicle Body, of which the following is a specification, reference being had to the accompanying drawing, forming part thereof, in which:

Fig. 1 is a side elevational view of a vehicle

body showing my new design, the opposite side thereof being of identical appearance; and

Fig. 2 is an enlarged detailed view of one of the panels outlined by the dot-dash lines in Fig. 1.

The dominant features of my design reside in the portions shown in full lines and particularly in the panel decoration.

I claim:

The ornamental design for a vehicle body, substantially as shown and described.

GIUSEPPE RUSSO.
